Primary Examiner — Ricky Pham(57) CLAIM

The ornamental design for a multifunctional oven as shown and described.

DESCRIPTION

FIG. 1 is a front, top, right perspective view of a multifunctional oven showing my new design;

FIG. 2 is a back, bottom, left perspective view thereof;

FIG. 3 is a front view thereof;

FIG. 4 is a back view thereof;

FIG. 5 is a right view thereof;

FIG. 6 is a left view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 2;

FIG. 11 is an enlarged view of the encircled area 11 of FIG. 3; and,

FIG. 12 is an enlarged view of the encircled area 12 of FIG. 7.

The broken lines shown on the drawings depict portions of the multifunctional oven that form no part of the claimed design.
